Patented Nov. 30, 1915.

UNITED STATES PATENT OFFICE.

CALEB E. SUMMERS AND CHARLES B. LARMON, OF WICHITA, KANSAS.

ACETYLENE-GAS TANK.

1,162,113.

Specification of Letters Patent. Patented Nov. 30, 1915.

Application filed June 28, 1911. Serial No. 635,774.

To all whom it may concern:

Be it known that we, CALEB E. SUMMERS and CHARLES B. LARMON, citizens of the United States, residing at Wichita, in the county of Sedgwick, State of Kansas, have invented a new and useful Acetylene-Gas Tank, of which the following is a specification.

The present invention relates to improvements in frost protecting means for acetylene gas generators, one object of the invention being the provision of a protector for the generator, whereby the water therein and also the condensation from the gas will be protected from freezing, thus permitting the installation of the present generator at a point exteriorly of the house and at a safe distance therefrom.

A further object of the present invention is the provision of a protecting casing or covering for the acetylene generator, in which the outer surface is weather resisting, the portion adjacent to the generator containing a heat insulating material, so that the heat within the generator will be retained and the cold on the outside prevented from affecting the water or the condensation from the gas within the generator.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings is illustrated a vertical central sectional view through the protecting means showing one form of acetylene gas generator used in connection therewith.

Referring to the drawings, the numeral 1 designates the outer metallic casing which is mounted on a base 5 above or below the surface of the ground and forms with the concentric inner casing or cylinder 2, preferably made of metal, a circular receptacle for the insulating material 7, such as mineral wool or asbestos, the upper end of said space between the casing being closed by means of a ring 4, preferably made of concrete or other plastic material.

Mounted within the cylinder 2 in the present instance, is the acetylene gas generator G, the same being indicative of any form of

generator that can be utilized in a protecting structure as herein set forth.

Surrounding the outer metal casing 1 and resting upon the base 5, which also constitutes a support for the metal casings 1 and 2 and a bottom for the annular space therebetween which holds the insulating material 7, is the cylindrical concrete member 6, the same extending above the upper rim or edge 60 of the cylinder 1 and having its upper face inclined on the same angle as the inclined upper face of the ring 4, so that any water falling thereupon will be properly drained away from the device.

Mounted at the upper end of the cylinder 2, whose rim extends at a point adjacent to the extreme upper end of the rim 4, is the cover 26, which is a hollow cover and contains the insulating material 3 which is similar to the material 7 and thereby inclosing the compartment formed by the cylinder 2 so as to exclude the effect of the cold and surrounding atmosphere from the acetylene gas generator, and to also, retain the heat 80 therewithin formed by the generation of the gas as the carbid falls into the water.

The protector for acetylene gas generators herein disclosed, comprises, briefly considered, a base 5 on which rests an outer cylinder 1 and an inner metal cylinder 2, the inner cylinder 2 being of greater height than the outer cylinder. The outer cylinder 1 is provided at its top with an outwardly projecting flange 100. The concrete casing 6 surrounds the outer cylinder 1 and is extended upwardly above the outer cylinder to a point adjacent the upper edge of the inner cylinder 2, the casing being laterally offset as shown at 101 to extend beneath the flange 100. The concrete ring 4 extends between the casing 6 and the inner cylinder 2, the ring being offset horizontally as shown at 102 to overhang the flange 100, and being downwardly offset as shown at 103 to extend between the cylinders 1 and 2. A reinforcing band 104 lies between the ring 4 and the casing 6, the band having a projection 105 extended into the ring. The band 104 is in lateral abutment with the flange 100, as shown at 106, and the lower edge 107 of the band is embedded in the laterally offset portion 101 of the casing 6. A heat insulating packing 7 is located in the compartment defined by the base 5, the ring 4, and the cylinders 1 and 2.

From the foregoing description, it is evi-

dent that when an acetylene gas generator is protected as herein illustrated and described, that the same may be constructed upon a comparatively large scale for use as a main heating plant for a suburban or country house, and as the same can be placed in an isolated position away from the house and out buildings, and exposed to the outside atmosphere, the gas will be properly generated for distribution and at the same time, the contents of the generator will be protected against the elements.

What is claimed is:

A protector for an acetylene gas generator, comprising a base; an outer metal cylinder resting on the base; an inner metal cylinder resting on the base and of greater height than the outer cylinder; an annular flange projecting outwardly from the outer cylinder at its top; a concrete casing surrounding the outer cylinder and extended upwardly above the outer cylinder to a point adjacent the upper edge of the inner cylin-

der, the casing being laterally offset to extend beneath the flange; a concrete ring extended between the casing and the inner cylinder, the ring being offset horizontally to overhang the flange, and being downwardly offset to extend between the cylinders; a reinforcing band lying between the ring and the casing, the band having a projection extended into the ring, the band lying in lateral abutment with the flange and having its lower edge embedded in the laterally offset portion of the casing; and a heat insulating packing located in the compartment defined by the base, the ring and the cylinders.

In testimony that we claim the foregoing as our own, we have hereto affixed our signatures in the presence of two witnesses.

CALEB E. SUMMERS.

CHAS. B. LARMON.
